UNITED STATES PATENT OFFICE.

FRANK JIROUSEK, OF OWATONNA TOWNSHIP, STEELE COUNTY, MINNESOTA.

GRAIN-STACKER.

1,068,138.

Specification of Letters Patent.

Patented July 22, 1913.

Application filed February 6, 1913. Serial No. 746,583.

To all whom it may concern:

Be it known that I, FRANK JIROUSEK, a citizen of the United States, and a resident of Owatonna township, in the county of Steele and State of Minnesota, have invented certain new and useful Improvements in Grain-Stackers, of which the following is a specification.

My invention relates to an improvement 10 in grain-stackers, and more particularly to a grain-stacker having the power for operating it mounted thereon.

My invention has for its object the provision of means by which the conveyer-trough of the stacker can be raised or lowered and held at any desired point.

It further has for its object the provision of a stacker which can be folded up into very compact form when it is desired to 20 transport the same from place to place or when it is desired to have it occupy as little space as possible.

A further object of my invention is to provide for mounting the motive power for 25 operating the conveyer-trough on the stacker, which is simple, inexpensive, and durable in construction and very easy and effective in operation.

The invention consists in the construction, 30 combination and arrangement of the several parts, as more fully hereinafter described and claimed.

Referring to the drawings—Figure 1 is a side view showing the several parts of 35 the stacker in the positions that they occupy when ready for use; Fig. 2, a top plan view; Fig. 3, a rear end view; Fig. 4, a side view, showing the several parts of the stacker in the positions that they occupy 40 when folded; Fig. 5, an enlarged detail front view of the pivoted frame in which the conveyer-trough is mounted and its supporting standard; Fig. 6, an enlarged detail side view of the pivoted frame in which the conveyer-trough is mounted and its supporting 45 standard; Figs. 7 and 8, detail front and end views of the slidable bar supporting the conveyer-trough; Fig. 9, a fragmentary view of the upper portion of the pivoted frame; 50 and Fig. 10, a top plan view of the main frame on an enlarged scale.

In the drawings, in which like numerals of reference indicate corresponding parts throughout the several views, 1 represents 55 the main frame of the stacker, comprising

longitudinal beams 2 and cross-beams 3, provided with axles 4, on which are mounted wheels 5. Standards 6, preferably made of L-shaped iron, are provided and extend upwardly from the beams 2, being braced by 60 means of a series of braces 7, and a bracket 8, having a slot or socket 9, is secured to the front edge of each of said standards 6 at the upper end.

9^a is a windlass secured to the left-hand 65 standard.

A frame 10 is pivoted to the standards 6 by means of bolts 11, and comprises a top piece 11^a and side pieces 12. The lower ends of the side pieces 12 of the frame 10 are 70 provided with holes 13, which register with holes 14 in the standards 6, and 15 are bolts which are inserted in said holes 13 and 14 and which serve to hold and lock the frame in its upright position, but which can be 75 withdrawn to allow the frame to be turned on the pivot bolt 11 and brought into its folded position when desired.

A pulley 16 is mounted in the left-hand side piece. Standards 17 are pivoted to the 80 beams 2 by means of a shaft or rod 18 and are provided with cross-rods 19, which connect and hold them together, and an upper shaft 20, having sprocket-wheel 21. Sprocket-wheels 22 22^a, mounted on the 85 shaft 18, an idle sprocket 23, and a sprocket-chain 24 operatively connect said sprocket-wheels 21, 22, and 23.

25 is the conveyer-trough, which is pivotally connected to the shaft 20 and is provided with an endless conveyer, of any well-known character, preferably comprising 90 endless sprocket-chains 26, having sweeps 27.

A bar 28, slidable on the side pieces 12 of the frame 10, is provided, said bar 95 having depending arm 29, which are secured to the conveyer-trough 25, this bar serving to support the conveyer-trough 25 at the desired point on the frame 10. The bar 28 is provided with a pulley 30, and 31 100 is a rope or cable which is secured to the top piece 11^a of the frame 10, and after running over pulley 30 and pulley 16 is wound around the windlass 9^a, when it will be apparent that by operation of the windlass 105 the conveyer-trough can be raised or lowered as desired. When the conveyer-trough is in its elevated position the bar 28 will frictionally engage the side pieces 12 of the frame 10, but when the conveyer- 110

trough assumes its folded position the ends of the bar 28 will engage and be seated in the slots 9 of the brackets 8.

31^a is a shaft supported on brackets 32, 5 having a pulley 33 and a sprocket-wheel 34 mounted thereon, and 35 is a sprocket-chain connecting the sprockets 34 and 22^a.

The endless conveyer is driven or operated by means of an engine 36, preferably a gaso- 10 lene engine, which is mounted on a platform 37 on the beams 2, and said engine is pro- vided with a pulley 37^a, which is operatively connected to the pulley 33 by means of a bolt 38.

15 The operation of my device is so obvious that I have not described same in detail. I do not desire to be limited to the precise details of construction and arrangement of the several parts as the same may be changed 20 without departing from the spirit of my invention.

Having thus described my invention, what I claim is—

1. In a device of the character described, 25 a frame provided with standards having slots, a frame pivoted to said standards, a bar slideable on said pivoted frame and adapted to engage the slots of the standards, a conveyer-trough provided with a conveyer 30 and suspended from said bar, and means for adjusting the bar and conveyer-trough, substantially as shown and described.

2. In a device of the character described, 35 stationary standards, a frame pivoted on said standards, a bar slideable on said frame, pivoted standards, a conveyer-trough provided with a conveyer and connected to said bar and pivoted to the pivoted standards, and means for adjusting the said bar and 40 conveyer-trough, substantially as shown and described.

3. In a device of the character described, pivoted standards, a conveyer-trough hav-

ing a conveyer and pivoted to said pivoted standards, standards having a frame pivoted thereon, and means connected to said conveyer-trough and slideable on said frame for adjusting the said conveyer-trough, substantially as shown and described. 45

4. In a device of the character described, 50 stationary standards having slotted brackets, a frame pivoted on said standards, a bar slideable on said pivoted frame, means for supporting said bar, pivoted standards, and a conveyer-trough having a conveyer 55 and pivoted to said pivoted standards and connected to said slideable bar, substantially as shown and described.

5. In a device of the character described, pivoted standards, stationary standards, a 60 frame pivoted to said stationary standards, a conveyer-trough having a conveyer and pivoted to said pivoted standards and extending within the said pivoted frame, and means connected to the conveyer-trough and 65 slideable on said pivoted frame for adjusting said conveyer-trough within the pivoted frame, substantially as shown and described.

6. In a device of the character described, 70 a frame provided with standards having slots, a frame pivoted to said standards, a bar slideable on said pivoted frame, means for operating said bar to engage the said slots of the standards aforesaid, pivoted standards, and a conveyer-trough having a 75 conveyer and pivoted to said pivoted standards and connected to said slideable bar, substantially as shown and described.

In witness whereof, I have hereunto set my hand in presence of two subscribing wit- 80 nesses.

FRANK JIROUSEK.
